J. J. FROELICH,
WATER GAGE FOR STEAM BOILERS,
APPLICATION FILED APR. 25, 1917.

1,247,256.

Patented Nov. 20, 1917.

Inventor

JOHN J. FROELICH

By Watson E. Coleman

Attorney

UNITED STATES PATENT OFFICE.

JOHN J. FROELICH, OF DICKINSON, NORTH DAKOTA.

WATER-GAGE FOR STEAM-BOILERS.

1,247,256.

Specification of Letters Patent. Patented Nov. 20, 1917.

Application filed April 25, 1917. Serial No. 164,442.

To all whom it may concern:

Be it known that JOHN J. FROELICH, a citizen of the United States, residing at Dickinson, in the county of Stark and State 5 of North Dakota, has invented certain new and useful Improvements in Water-Gages for Steam-Boilers, of which the following is a specification, reference being had to the accompanying drawings.

10 This invention relates to boilers, and particularly to devices for determining the depth of water over the crown sheet of a boiler.

The general object of the invention is to 15 provide an improved form of gage which will indicate the depth of water in the boiler and will show exactly the height of the boiler above the crown sheet thereof, thus doing away with the use of gage glasses, 20 which are very liable to break under the pressure to which they are subjected and which gage glasses are open to objection because the water level cannot be readily discerned through the relatively thick and usually 25 dirty glass of the gage.

A further object is to provide a water level indicator of the character described, so arranged that a pressure gage may be connected with it;

30 And a further object is to provide a water level indicator including a float, a pointer operating over a dial and controlled by the float, and means for draining the casing wherein the operating mechanism is contained.

Still another object is to provide means whereby the tubular guide through which the float rod operates may be adjusted vertically through the upper wall of the boiler 40 to thereby cause the device to be adapted to attachments of different makes of boilers having different depths of water level above the crown sheet.

Other objects will appear in the course of 45 the following description.

My invention is illustrated in the accompanying drawings, wherein:

Figure 1 is a sectional view of a boiler and my improved gage;

50 Fig. 2 is a front elevation of a portion of the gage;

Fig. 3 is a side elevation, partly broken away.

Referring to the drawings, it will be seen 55 that my improved gage comprises a tubular member 10, which is adapted to be inserted

through an opening in the upper sheet or shell 11 of a boiler 12, this tubular member 10, which constitutes a guide, being disposed through a stuffing box 13 of any usual or ordinary form and having a gland 14. The upper end of the guide tube 10 is exteriorly screw-threaded to extend into the wall 15 of a casing 16. The upper and lower ends of the tube 10 are open, but the lower end of 65 the tube 10 is formed with the inwardly extending tubular flange 10^a, there being no such flange on the upper end of the tube. The lower end of the tube is provided with a ball bearing 17 of any suitable construction and reciprocating through this ball bearing and through the tube 10 is a float rod 18, the lower end of which is attached to a float 20 which rests upon the crown sheet 19 of the boiler when the water is entirely 70 out of the boiler, and lifts as the water increases in depth. This float rod 18 carries upon it a collar 17^a carrying anti-friction balls engaging with the side wall of the tube 10. 75

The collar 17^a constitutes a stop above the ball bearings 17 so as to limit the downward movement of the rod and prevent its dropping out of the guide tube 10. The casing 16 is circular in form and extending through 80 the casing 16 is a shaft 21, upon which is mounted the gear wheel 22. This shaft extends out through a stuffing box 23 formed upon a dial plate 24 and carried upon the outer end of the shaft 21 is a pointer 25 85 operating over the dial plate. The margin of the dial plate is provided with a series of numerals arranged in successive order and the pointer 25 coacts with these numerals. A glass plate 26 preferably extends over 90 the pointer so as to entirely house it and the dial. The upper end of the float rod 18 is provided with rack teeth 27, which engage the gear wheel 22. The upper extremity of the float rod 18 is engaged by a float rod 95 guide 28 attached to the wall of the casing and having a fork through which the float rod passes, this float rod guide 28 holding the rack teeth 27 in proper engagement with the teeth on the gear wheel 22. Above the 100 thickened portion 15 of the casing, the casing is provided with a thickened portion 29, which is interiorly screw-threaded for the attachment of a tubular member 30, which, as illustrated, connects with a pressure gage 110 31. Preferably the casing 16 is formed in two sections, hinged to each other by the

hinge 32 and held closed in any suitable manner and there should be gaskets disposed between the two sections so as to make the joint steam-tight. A drain pipe 33 extends 5 downward from the lowermost portion of the casing 16 and discharges into the pipe 10, this drain pipe being preferably formed in two sections connected by a union 34. Preferably also a ball bearing 35 is provided 10 for supporting the ends of the shaft 21, so as to permit the shaft 21 to rotate easily and prevent the pressure against the gage rod acting to impede its free movement.

15 Assuming that the device is intended to indicate a maximum depth of 8" of water over the crown sheet, then the gear wheel 22 should be 8" in circumference and the rack teeth 27 should extend over a length of 20 8". If the maximum depth of water to be measured is greater or less than 8" it is obvious that the proportions of the rack teeth and gear wheel will be accordingly changed. The extension 30 of the tubular 25 member must be sufficiently long of course as to permit the rack to move upward to its full stroke.

The gage is to be set as close to the boiler as possible.

30 The operation of this invention may be obvious from what has gone before. If the water lowers in the boiler, the float 20 will move downward correspondingly, which will lower the float rod 18 and rotate the pointer 35 25 in a counter-clockwise direction. If, on the other hand, the water in the boiler rises, the float will rise and rotate the hand in a clockwise direction. The dial is graduated so that the distance of the float from the 40 crown sheet of the boiler may be read in inches and fractions thereof. The tube 10 is adjustable through the supporting box 13 so that the tube 10 may be pushed up or down and so adjust the device that the float 45 will strike the lower sheet of the boiler when the pointer 25 points to zero. The float 20 is of such weight that it will not jump up and down when the water in the boiler is boiling, but will remain relatively steady.

50 My device does away with the necessity of using gage glasses and shows positively and plainly the level of water within the boiler and the exact depth of water over the crown sheet. The device is very simple, can be cheaply made, can be used with or without the pressure gage and it is obvious that inasmuch as the device may be made of metal, there will be no chance of breakage from internal pressure as there is with gage 55 glasses, nor will there be any chance as there is in gage glasses, of the device becoming so dirty as not to be easily read. It will be understood, of course, that the casing 16 and the tube 10 will be full of steam. 60 The gage is to be disposed directly over the

crown sheet at the rear end of the boiler and is adapted to be used on any standard boiler or on traction engines or locomotive boilers.

While I have illustrated a form of my invention which I have found to be thoroughly effective in practice, yet it is obvious that I do not wish to be limited to the details of construction illustrated, as these may be varied in many ways, without departing from the spirit of the invention. This is particularly true of the gearing whereby the pointer is rotated.

Having described my invention, what I claim is:—

1. The combination with a steam boiler having upper and lower sheets, of a guide tube extending through the upper sheet and vertically adjustable therein, the lower end of said tube being formed with a stop, a float rod extending upward through the guide tube and having a float at its lower end, a rotatably mounted pointer, means operatively connecting the pointer to the float rod, and a stop mounted upon the float rod within the guide tube and engageable with the stop on the lower end of the guide tube to thereby limit the downward movement of the float and rod.

2. A water gage for boilers comprising a tubular member adapted to be inserted through the upper sheet of a boiler and vertically shiftable therein, and having ball bearings at its lower end, a float rod extending entirely through the tubular member and carrying a float at its lower end, the upper end of the rod being provided with teeth, a casing into which the upper end of the tubular member opens, a shaft passing through the casing, a pointer on the shaft, 95 graduations on the face of the casing over which the pointer moves, and a gear wheel on the shaft operatively engaged with the teeth on the float rod.

3. A water gage for steam boilers including a tubular guide adapted to be inserted through the upper sheet of a boiler, a float rod extending upward through the guide, means for limiting the downward movement of the rod relative to the guide, a float carried on the lower end of the rod, the upper end of the rod being formed with teeth, a casing in which the upper end of the tubular guide opens, a shaft passing through the casing, a pointer carried on the shaft and 110 operating over a dial, a gear wheel operatively connected to the shaft and engaged by said teeth on the float rod, and a drain pipe extending from the lowermost portion of the casing and opening into said guide 115 tube.

4. The combination with a boiler having an upper and a lower sheet, of a stuffing box mounted on the upper sheet, a guide tube disposed in the stuffing box and vertically 120 125 130

shiftable therethrough, a float rod extending upward through the guide tube and having a float at its lower end, a casing into which the upper end of the guide tube opens, a tube extending upward from the casing and in alinement with the guide tube, a dial, a pointer operating over the dial, and means controlled by the float rod for rotating the pointer over the dial.

5. The combination with a steam boiler having upper and lower sheets, of a guide tube extending through the upper sheet and vertically adjustable therein, the guide tube being open at its upper and lower ends, a 10 casing into which the guide tube opens, a float rod extending upward through the guide tube and casing and having a float at its lower end, a shaft mounted in the casing and extending through the walls 15 thereof and carrying a pointer on one end, operative driving means between the float rod and said shaft to rotate the latter upon the reciprocation of the float rod, and a drain pipe leading from the lowest portion 20 of the casing and discharging into said guide tube.

6. The combination with a steam boiler having upper and lower sheets, of a guide tube extending through the upper sheet, a 25 casing into which the upper end of the guide tube opens, a tube extending upward from the casing and in alinement with the

guide tube and carrying a pressure gage, a shaft extending through the casing, a float rod disposed in the guide tube, a shaft extending through the casing, to which the float rod is operatively connected, and a pointer carried on the shaft.

7. The combination with a steam boiler having upper and lower sheets, of a guide tube extending upward through the upper sheet, the upper end of said guide tube being open, the lower end having an annular flange, a casing into which the upper end of the guide tube opens, a tube extending upward from the casing and in alinement with the guide tube, a float rod passing through the guide tube and into said casing, a shaft carrying a pointer and extending through the casing, a gear wheel on the shaft operatively engaged by the float rod, ball bearings mounted in the lower end of the guide tube, and a member mounted upon the float rod and having anti-friction elements movable with the float rod and engageable with the walls of the guide tube, and a float mounted upon the lower end of the float rod.

In testimony whereof I hereunto affix my signature in the presence of two witnesses.

JOHN J. FROEHLICH.
